UNITED STATES PATENT OFFICE.

LAWRENCE T. FAY, OF ELYRIA, OHIO, ASSIGNOR TO THE FAY RUBBER PRODUCTS COMPANY, OF ELYRIA, OHIO, A CORPORATION OF OHIO.

RESILIENT HEEL.

1,325,695.

Specification of Letters Patent. Patented Dec. 23, 1919.

Application filed May 31, 1918. Serial No. 237,434.

To all whom it may concern:

Be it known that I, LAWRENCE T. FAY, a citizen of the United States, residing at Elyria, in the county of Lorain and State 5 of Ohio, have invented a certain new and useful Improvement in Resilient Heels, of which the following is a full, clear, and exact description, reference being had to the accompanying drawings.

10 This invention relates to resilient heels, and one of the objects is to construct a resilient heel in such a manner as to increase its resiliency without sacrificing its wearing qualities. A feature of the invention 15 is that resilient heels constructed according to this invention may be made of more unyielding rubber or like material than that ordinarily used and still be more resilient and yielding than softer rubber. Another 20 object is to so arrange the heel that it may be very capable of easy application and adapted to resist any tendency to slip.

25 My invention is hereinafter more fully described in connection with the accompanying drawings. Other objects will become apparent in such description and the essential characteristics are summarized in the claims.

30 In the drawings, Figure 1 is a vertical longitudinal section through my heel affixed in position; Fig. 2 is a bottom plan of the heel; Fig. 3 is a top plan of the resilient heel removed; Fig. 4 is a transverse section taken substantially on the line 4—4 of 35 Fig. 2; Fig. 5 is a bottom plan of a securing plate for the rubber heel.

Describing the parts by the use of reference characters, A and B indicate the counter and sole in broken lines; C indicates the 40 solid portion of the heel usually constructed of leather and having a flat bottom surface, to which my rubber heel may be affixed. As shown my rubber heel is as the same exterior contour as the solid portion 45 and comprises a body of rubber 10 formed to present a wide rib 11 surrounding a recess 12, the sides of which are substantially in conformity with the rim of the heel. As shown, this rib is undercut so that its 50 edges are beveled at 13, sloping upwardly to a substantially flat surface 14, the area of the upper surface 14 of the recess being greater than the opening of the recess.

Between the surface 14 and the upper 55 surface of the rubber heel, I have shown a

plate 16 of metal or similar stiff material embedded in the rubber, and projecting upwardly from this plate are suitable securing members, such as pegs or nails 17 and 18. The peg 17 is shown as the central peg which I prefer to make longer and larger than the others for convenience in centering the rubber heel and positioning the same before driving the securing pegs 18 in the solid portion. These pegs 60 are preferably of the same material as the plate and are rigidly secured thereto as by soldering so that the rubber heels when completed are equipped with projections extending upwardly from the rubber and 65 adapted to be driven into position by striking the rubber preferably over the heads of the pegs, although striking the rubber at any portion of the bottom of the surface 14 of the recess, transmits its force through 70 the plate to the pegs and facilitates the driving thereof.

To still further add to the resiliency of the tread portion of the heel, in other words to render the raised broad ribs 17 very 80 yielding in proportion to the stiffness of the material, I provide cavities 20, shown as opening upwardly and closed by the lower surface of the solid portion of the heel whereby air is imprisoned in these cavities 85 when the heel is in position, forming a pneumatic cushion resisting the compression of the ribs 11 as the wearer puts his weight thereon. By this means, the resiliency of the heel is increased and I am able to use 90 more rigid and tenacious material. Because of such added resiliency and enabling the use of wear resisting material, the life of the heels is greatly extended, it being a well-known fact that up to certain limits, the 95 resiliency of the heel adds to the wearing qualities. The formation of the cavity particularly with the downwardly and inwardly sloping walls, also adds to the compressibility of the tread portion which has 100 the following desirable effect, namely, that as the wearer steps on the heel, the entire tread portion is compressed and air is forced from the cavity 18, causing vacuum in the cavity which tends to prevent slipping and 105 which does not interfere with the raising of the foot as the vacuum is readily broken when the rear portion of the heel is lifted.

By embedding the plate 16 in the rubber, the plate and the pegs are protected from 110

exposure to corrosion and this is a desirable characteristic for the reason that if metal, used in securing the heel, is allowed to corrode, it presents a surface to which snow and ice more readily adhere than to the surface of the rubber.

It will also be noted that this form of heel presents the desired thickness and size with less actual volume of rubber with a resultant saving of this material.

I have used the terms "rubber" and "resilient material" interchangeably in the foregoing specification for the reason that my heel may be constructed of any resilient material and a change of such material does not constitute a departure from the spirit of this invention.

Having thus described my invention, what I claim is:

1. A resilient heel having a substantially flat upper surface adapted to fit the solid portion of the heel, securing means embedded in the rubber and having projections extending upwardly therefrom, a substantially flat tread surface and a cavity within the tread surface, the sides of the cavity sloping upwardly and outwardly from the treading surface.

2. A resilient heel, consisting of a body portion, a raised rib having a substantially flat broad surface extending entirely around the perimeter of the heel and air cavities formed in said rib opening upwardly and closable by the lower surface of the solid heel portion of the shoe and a plate embedded in said body portion, being

covered both above and below by the material of the resilient heel and having its edges extending past the inside edge of the rib portion to a point adjacent the cavity. 40

3. A resilient heel having a substantially flat tread surface extending around the perimeter of the heel and a cavity within said tread surface, the sides of the cavity sloping upwardly and outwardly toward the sides 45 of the heel, a securing plate embedded in the rubber of the heel, being covered above and below by the rubber and extending outwardly past the upper larger portion of the cavity, and a series of upwardly opening 50 cavities formed between the edge of said plate and an outside perimeter of the heel and closed by the lower surface of the solid portion of the heel of the shoe.

4. The combination, with a solid heel section, of a resilient heel section comprising a body, and a downwardly extending rib having a comparatively broad flat surface extending entirely around the perimeter of the heel, and having cavities formed in the 60 material above the rib and approximately centrally spaced with relation to the inner and outer walls of the rib, opening upwardly from the resilient section and closed by the solid section of the heel, such 65 cavities forming a substantially continuous series extending around the heel and spaced apart sufficiently to provide an intermediate connecting bracing portion between them.

In testimony whereof, I hereunto affix my 70 signature.

LAWRENCE T. FAY.
